UNITED STATES PATENT OFFICE.

WILLIAM SPALCKHAVER, OF NEW YORK, N. Y., ASSIGNOR TO ROBERT HOE,
OF NEW YORK, N. Y.

CONTROLLING DEVICE FOR LIQUID-SUPPLY ROLLS.

SPECIFICATION forming part of Letters Patent No. 742,249, dated October 27, 1903.

Application filed February 27, 1903. Serial No. 145,336. (No model.)

To all whom it may concern:

Be it known that I, WILLIAM SPALCKHAVER, a citizen of the United States, residing at New York, county of Kings, and State of New York, have invented certain new and useful Improvements in Controlling Devices for Liquid-Supply Rolls, fully described and represented in the following specification and the accompanying drawings, forming a part of the same.

This invention relates to certain improvements in controlling devices for liquid-supply rolls.

In certain classes of machines it is customary to employ a liquid-supply roll and a ductor or delivery roll which takes the liquid from the supply-roll and delivers it. Thus, for instance, in the constructions used in planographic-printing machines, and ordinarily known as "water-motions," there is employed a fountain-roll which takes up water from a fountain and a delivery or ductor roll which takes the water from the fountain-roll and delivers it to other rolls, by which it is placed upon the form.

The present invention has for one of its objects to produce a simple, cheap, and effective construction by which the amount of liquid delivered by devices of the class referred to shall be controlled.

A further object of the invention is to produce an improved construction by which the amount of liquid delivered by devices of the character above referred to shall be controlled, which construction can be readily adjusted without stopping or otherwise interfering with the operation of the machine.

With these and other objects in view the invention consists in certain constructions and in certain parts, improvements, and combinations, as will be hereinafter fully described, and specifically pointed out in the claims hereunto appended.

In the accompanying drawings, in which like characters of reference indicate the same parts, Figure 1 is a front elevation of a water-motion of a printing-machine embodying the invention, certain parts of the construction being broken away. Fig. 2 is an end elevation of the construction shown in Fig. 1. Fig. 3 is a view similar to Fig. 2 and show-

ing the parts in a different position. Fig. 4 is a view similar to Fig. 2, but showing the parts in a different adjustment. Figs. 5 and 6 illustrate a modification of the construction shown in Figs. 1 to 4.

Referring to the drawings which illustrate one embodiment of the invention, 1 indicates the frame of the machine. The liquid-supplying devices may be of any suitable construction. As shown, they consist of a pan 2, in which rotates the usual supply-roll 3, which is journaled in suitable bearings on the frame. The delivery or ductor roll 4 may be mounted in any suitable manner, so as to move between the supply-roll 3 and a roll 5, which is one of the rolls by which the liquid is distributed and delivered to the form. In the present construction the delivery or ductor roll 4 is mounted in arms 6, which are rigidly secured to a rock-shaft 7, journaled in suitable bearings in the frame.

The mechanism by which the rock-shaft 7 is operated may be of any suitable character; but as shown it includes a suitable operating-cam and a controller, which together effect the movements of the delivery-roll from the supply-roll to the distributing-roll and which govern the time during which the delivery-roll remains in contact with the supply-roll, and therefore determine the amount of liquid taken up by the delivery-roll. In the construction shown this operating-cam is a rotating cam, (marked 30,) said cam being fast on and rotating with a shaft 31, which is suitably supported in the frame of the machine.

The controller in the preferred construction comprises a block 32, which, as shown, is pivoted at 33 to the cam 30, so that it may be given movements independent of the movement which it has when moving with the cam. The means for giving the controller its independent movement may be varied widely. In the preferred form of the construction, however, this means will include an adjustable cam 34, said cam being loosely mounted on the shaft 31, before referred to. The controller-block 32 is provided with a cam-roll 35, which co-operates with the cam 34.

In the operation of the device the cam 34 is stationary with respect to the shaft and

the cam 30 and the controller-block revolve with it. The roll 35, running on the cam 34, causes the controller to be given movements the time and extent of which will depend 5 upon the position and contour of the cam 34. The position of the cam 34 may be adjusted in any suitable manner. As shown, this cam is provided with a hub 36, which is surrounded by a hub 37, said hub having a set-screw 10 37' tapped through it, so that the hubs 36 and 37 are connected thereby. Extending from the hub 37 is an arm 38, provided with a handle 39. By operating this handle the cam 34 may be adjusted axially around the shaft 31 15 in any desired position. Suitable locking means are provided for holding the cam in its adjusted position, and these locking means may be of any suitable character. As shown, the arm 38 carries a bolt 40, which runs in 20 the slot 41 of a sector 42, secured to the frame. On the end of this bolt 40 is a tightening-nut 43, by which the arm and handle may be locked in any desired position in the sector-slot.

25 The means by which the cam and controller operate to effect the movement of the delivery-roll may be varied and will vary according to the location and arrangement of the fountain.

30 Referring to Figs. 1 to 4, inclusive, in which the fountain is shown as above the distributing-rolls, there is provided an operating-lever 44, which is pivoted at 45 to the frame of the machine. This lever is provided with a bowl or roller 46, which is long enough to run both on the surface of the cam and on the surface of the pivoted controller-block 32. This lever 44 in the construction shown is connected, by means of 35 40 a link 47, to an arm 48, which is fast on the rock-shaft 7, before referred to.

The operation of the construction thus far described will be clearly seen from the illustration in Figs. 2, 3, and 4. Referring to 45 Fig. 2, the cam 30 and the controller-block are in such position with respect to the cam 34 that the roll 35 is about to drop from the raised portion of the cam 34. In Fig. 4 the roll 35 has passed off the raised portion of 50 the cam 34, and it will be seen that the controller-block 32 has moved inward, it being guided in its movement and the extent of the movement being determined in any suitable manner—as, for instance, by means of a pin 55 49, which co-operates with a slot 50 in the block—and this inward movement has allowed the lever 44 to descend and rock the shaft 7, thus moving the roll 4 away from the supply-roll 3. As the cam 30 continues to 60 rotate the lever 44 will be allowed to rock downward still farther, so that the roll 4 will be brought into contact with the distributing-roll 5. When the construction is adjusted as shown in Figs. 2 and 3, the roll 4 will remain in contact with the roll 3 for a comparatively short time, and therefore will take up but little liquid. If, however, it is de-

sired to increase the time of contact between the rolls 4 and 3, the arm 38 is thrown over by its handle 39, thus carrying the cam 34 70 axially about the shaft 31. Such an adjusted position is shown in Fig. 4. In this figure the cam 34 is so adjusted that its high portion will act on the controller-block 32 at the time the arm 44 has been raised by the high portion of the cam 30. In other words, in this figure after the high portion of the cam 30 has raised the arm 44 into a position where the roll 4 is nearly in contact with the roll 3 the controller-block comes into operation and 75 raises the arm 44 still farther, so as to bring the roll 4 into full contact with the roll 3. At this time the roll 35 of the controller-block has just begun to run on the high concentric portion of the cam 34, and during the time 80 when it is passing over this portion the controller-block will remain raised, so that the roll 4 will remain for a much longer time in contact with the roll 3 than in the case of the adjustment before described, and so will take 85 up more liquid.

In the construction shown in Figs. 5 and 6 the fountain 2 and the supply-roll 3 are located below the distributing-rolls 5. In this case the operating connections are somewhat 90 different. The arm 48, which extends from the rock-shaft 7, has connected to it a slide 51, which is guided in its movement by means of a pin 52, mounted on an arm 53, extending from the frame, said pin co-operating with a 100 slot 54 in the slide 51. The lower end of the slide is provided with a bowl 55, which is operated upon by the cam 30 and the controller-block. In the construction illustrated in Figs. 1 to 4 the variations in the time of contact 105 between the rolls 4 and 5 took place when the roll 4 was raised—that is to say, after it had been operated upon by the high portion of the cam 30—whereas in the present construction the variations in the time of contact take 110 place when the roll is lowered or after it has been operated upon by the low portion of the cam 30. The cam 30 is accordingly given a somewhat different shape, and the controller-block instead of being moved toward the center of rotation of the cam 30 to interrupt the contact between the rolls 3 and 4 is moved 115 away from the center of rotation to accomplish the same result. This also necessitates a difference in the configuration of the cam 34. 120

Referring to Fig. 6, it will be seen that the bowl 55 has run off the high portion of the cam 30, and therefore that the slide 51 has been permitted to drop, so that the roll 4 rests upon the roll 3. In the position of the 125 parts shown in Fig. 6, however, the controller-block 32 is about to run onto the high portion of the cam 34, so that the controller-block will be raised and will strike the bowl 55, raising the slide 51 and interrupting the contact between the rolls. If, however, it is desired to increase the time of contact between the rolls 3 and 4, the handle will be shifted, as in the construction formerly de-

scribed, carrying the cam 34 to the left of the observer as the construction appears in Fig. 6. The farther the cam is adjusted to the left the longer it will be after the roll 55 has run off the high portion of the cam 30 before it will be struck by the controller-block, so that the longer the time will be during which the rolls 3 and 4 are in contact.

While the constructions which have been heretofore described constitute the preferred forms of carrying the invention into effect, it will be understood that many changes and variations may be made therein without departing from the invention. The invention is not to be limited, therefore, to the specific constructions herein shown and described.

What is claimed is—

1. The combination with a liquid-supply roll, of a delivery-roll, a movable cam, and suitable connections for producing movement of said delivery-roll toward and away from the supply-roll, a controller moving with the cam for governing the time of contact between the rolls, and means for giving the controller a movement independent of the movement of the cam, substantially as described.

2. The combination with a liquid-supply roll, of a delivery-roll, a rotating cam and suitable connections for producing movements of said delivery-roll toward and away from the supply-roll, a controller moving with the cam for governing the time of contact between the rolls, and means for giving the controller a movement independent of the movement of the cam, substantially as described.

3. The combination with a liquid-supply roll, of a delivery-roll, a movable cam and suitable connections for producing movements of the delivery-roll toward and away from the supply-roll, a controller for governing the time of contact between the rolls, and a cam for operating the controller, substantially as described.

4. The combination with a liquid-supply roll, of a delivery-roll, a movable cam and suitable connections for producing movements of the delivery-roll toward and away from the supply-roll, a controller for governing the time of contact between the rolls, and an adjustable cam for operating the controller, substantially as described.

5. The combination with a liquid-supply roll, of a delivery-roll, a rotating cam and suitable connections for producing movements of the delivery-roll toward and away from the supply-roll, a controller moving with the cam for governing the time of contact between the rolls, and an adjustable cam for operating the controller, substantially as described.

6. The combination with a liquid-supply roll, of a delivery-roll, a rotating cam and suitable connections for producing move-

ments of the delivery-roll toward and away from the supply-roll, a controller comprising a block pivoted to the rotating cam, and an adjustable cam for producing movements of the controller, substantially as described.

7. The combination with a liquid-supply roll, of a delivery-roll, a rotating cam and suitable connections for producing movements of the delivery-roll toward and away from the supply-roll, a controller comprising a block pivoted to said cam for governing the time of contact between the rolls, a cam in the path of the controller, and means for giving said second cam an axial movement to determine the time of operation of the controller, substantially as described.

8. The combination with a liquid-supply roll, of a delivery-roll, a lever and suitable connections for producing movements of the delivery-roll toward and away from the supply-roll, a cam and controller for operating said lever, and an adjustable cam for determining the time of operation of the controller, substantially as described.

9. The combination with a liquid-supply roll, of a delivery-roll, a lever and suitable connections for producing movements of the delivery-roll toward and away from the supply-roll, a cam and controller for operating said lever, a cam for determining the time of operation of the controller, and means for giving said cam an axial adjustment, substantially as described.

10. The combination with a liquid-supply roll, of a delivery-roll, a lever and suitable connections for producing movements of the delivery-roll toward and away from the supply-roll, a cam and controller for operating said lever, a cam for determining the time of operation of the controller, a handle for giving said second cam an axial adjustment, and means for locking said cam in its adjusted position, substantially as described.

11. The combination with a liquid-supply roll, of a delivery-roll, a rock-shaft by which said roll is moved, an arm on the rock-shaft, an operating-lever, connections between the lever and the arm, a rotating cam, a controller pivoted thereto, said cam and controller serving to operate the lever and through it the rock-shaft, a cam for determining the time of operation of the controller, and means for giving said second cam an axial adjustment and for locking it in adjusted position, substantially as described.

In testimony whereof I have hereunto set my hand in the presence of two subscribing witnesses.

WILLIAM SPALCKHAVER.
